UNITED STATES PATENT OFFICE.

WILHELM KUMMERER, OF BERLIN, GERMANY, ASSIGNOR TO RADIO CORPORATION OF AMERICA, A CORPORATION OF DELAWARE.

OSCILLATION CIRCUITS.

Application filed August 18, 1925, Serial No. 50,982, and in Germany October 1, 1924.

It is well known that the anode alternating current as well as the grid alternating current potential of oscillation tubes must have very definite values at a given anode 5 direct current potential, if the oscillation tube is to operate under optimum conditions. However, these values are unvaried within rather wide limits as the wave-length is changed. The consequence is that the ratio 10 between anode alternating current potential and grid alternating current potential should remain invariably the same as the wave-length undergoes changes.

An object of the present invention is to 15 maintain the proper grid potential automatically.

Other objects will be apparent from the following specification and drawings in which

20 Fig. 1 represents diagrammatically the fundamental connections of a tube transmitter involved in this invention.

Fig. 2 shows a slightly different set of connections embodying this invention.

25 Fig. 3 shows an embodiment of this invention as applied to a modified circuit.

Referring more particularly to the figures, in Fig. 1 there is diagrammatically shown the connections of a tube transmitter in 30 which *a* is the oscillation tube, *b* the coil of the oscillation circuit which is provided with several taps *p* for the connection of the anode, and taps *q* for the wave length adjustment; *c* is a variable condenser whose value is 35 changed either continuously or by steps, and which is intended for wave-length adjustment, *d* the anode blocking condenser, *e* the anode choke coil designed to prevent a short-circuit by way of the direct current source *f*.

40 It is customary to couple the back coupling coil for the grid alternating current potential to the oscillation circuit coil loosely. But this arrangement involves the drawback that upon every change in wave length the degree of the coupling of necessity must be varied and set in order that the proper grid potential may be obtained, unless the tube is to be operated with a more or less incorrect grid potential. However, in order that 45 the proper grid potential may always be obtained automatically, so to speak, it is also customary to divide the anode alternating current potential between points *x* and *y* either by inductive or capacitive means in 50 the manner of a potentiometer connection.

However, if this voltage divider element is passed only by a feeble current of high frequency, the ratio of potential division is changed owing to the load by the grid, with the consequence that on varying the wave 60 length the proper grid potential is not obtained or preserved within the entire range. Hence, in order to avoid this, as will be seen, it is necessary to allow a considerable proportion of the total current to flow through the 65 voltage divider, which, however, involves the great shortcoming that the range of variation of the wave length by the rotary condenser or the variometer is considerably impaired.

70 According to the present invention the correct and proper grid potential is produced at all times in this manner. The anode alternating current potential is stepped down by the aid of a transformer of fixed coupling 75 ratio to the value suited for the grid. As shown in Fig. 1, *g* is the primary winding of the coupling transformer which is connected at points *x* and *y*, and *h* is the secondary winding to which the grid *i* is united.

80 Another form of construction of the idea underlying the present invention consists in that the grid coupling transformer serves at the same time as the anode choker, as shown in Fig. 2. It can readily be seen that at the grid choker *e* the full anode alternating current potential is obtained between points *u* and *v*, for the direct current source *f* constitutes an almost complete short-circuit for the high frequency current. Apart from a 85 notable simplification, this arrangement furthermore offers the great advantage that parallel to the oscillation-circuit coil or variometer *b* there no longer are connected both the anode choking coil *e* and the primary winding of the coupling transformer *g*. This is of utmost advantage in order to insure a 90 large range of variation for the variometer.

95 The said coupling transformer moreover may be used for the object of changing the amplitude of the potential alternations of the oscillation circuit. For instance, in the case of transmitters worked at a high anode direct current potential, the alternating current potential of the oscillation circuit may be 100 accommodated to be a satisfactory value to accompany this high anode potential. An embodiment of this scheme is illustrated diagrammatically in Fig. 3 where *g*¹ and *g*² 105 stand for the two primary-winding halves 110

of the transformer of constant coupling ratio, while h again denotes the secondary winding to which the grid is connected. By such a transformer arrangement the alternating potential amplitude applied to the output circuit of the oscillator may differ from the potential amplitude applied to the direct current branch of the oscillator, to which branch the grid or control electrode circuit 10 is coupled for oscillation.

Having thus described my invention, what I claim is:—

1. An oscillation generator comprising a valve having an anode, a cathode, and a control electrode, an input anode-cathode circuit including a source of direct current, an output anode-cathode circuit including a resonant circuit, means to couple said input and output circuits including a transformer of 15 desired ratio, and a control electrode-cathode circuit including means coupled to the anode-cathode circuits.

2. An oscillation generator comprising a valve having an anode, a cathode, and a control electrode, an input anode-cathode circuit 25 including a source of direct current, an output anode-cathode circuit including a resonant circuit, means to couple said input and output circuits including a transformer of desired ratio, and a control electrode-cathode circuit including an additional transformer 30 coil coupled to the transformer of the anode-cathode circuits.

3. A vacuum tube oscillation generator comprising a vacuum tube, an anode-cathode 35 circuit having parallel connected alternating current and direct current branches, a control electrode-cathode circuit coupled to the direct current branch of the anode-cathode circuit, and a transformer to couple the direct 40 current and alternating current branches of the anode-cathode circuit in desired ratio.

WILHELM KUMMERER.
